United States Patent Office.

JOHN D. STEWART, OF LA PORTE, INDIANA.

Letters Patent No. 80,677, dated August 4, 1868.

IMPROVEMENT IN BALANCE-SLIDE VALVES.

The Schedule referred to in these Letters Patent and making part of the same.

TO ALL WHOM IT MAY CONCERN:

Be it known that I, JOHN D. STEWART, of La Porte, in the county of La Porte, and State of Indiana, have invented a new and useful Improvement in Slide-Valves for Steam-Engines; and I do hereby declare that the following is a full, clear, and exact description of the same, reference being had to the annexed drawings, making part of this specification, in which—

Figure 1 is a perspective view of the valve-chest.

Figure 2 is a vertical longitudinal section of the valve and chest.

Figure 3 is a section of the same, on the line z z , fig. 2, showing the top of valve-chest on one side, and the plate on the other side.

The same letters are employed in all the figures for the indication of the same parts.

My improvement consists in the construction and arrangement of the valve and chest, and in the combination with the same of packing-plates, held in contact with the valve by the pressure of the steam on the top of said plates.

In the annexed drawings—

A is the valve-stem, to which a reciprocating motion is communicated in the ordinary manner.

B is a slide-valve, actuated by the valve-stem. It is a metallic rectangular block, fitting neatly in the chamber of the valve-chest, and sliding on the bottom thereof. It is constructed with two vertical slots B^1 through the lap of the valve, through which the steam passes to the induction-ports C C, and with a chambered recess, B^2 , forming, with the movement of the valve, a communication for the passage of the steam alternately from the ports C C to the ejection-port D.

The steam is admitted from the steam-pipe at E into a steam-chamber, F, on the top of the valve-chest, from which it passes alternately with the movement of the valve, through openings F' F', into the passages B' B' through the valve into the induction-ports C C.

Two plates, H H, are placed in the top of the chamber of the valve-chest G, being received in recesses formed for the purpose in the top of the chest G¹. These plates are pressed by steam entering from the openings F' into longitudinal grooves, shown at G², fig. 3, upon the top of the valve B. These plates are for the purpose of relieving the valve from the friction which would be caused by having them fit tightly into the valve-chest, and by the pressure of the full force of the steam on the back of the valve, and to permit the expansion and contraction of the valve, while, at the same time, preventing the passage of the steam over the top of the valve from one opening B' to the other. An equivalent arrangement would be to substitute for the longitudinal grooves G² a series of holes opening from the steam-chamber F through the cover G¹, admitting the pressure of the steam to the top of the plates H. The upper and lower faces of the valve should be ground to make steam-tight surfaces.

What I claim as my invention, and desire to secure by Letters Patent, is—

In combination with the slide-valve B, valve-chest G, and cover G¹, and steam-chamber F, the packing-plates H, to the back of which steam is admitted from the steam-chamber, substantially as and for the purpose set forth.

In testimony whereof, I have signed my name to this specification in the presence of two subscribing witnesses.
